PRESSURE CASTING MACHINE

William M. Lester, Shaker Heights, Ohio, assignor to Lester Engineering Company, Cleveland, Ohio, a corporation of Ohio

Application February 7, 1935, Serial No. 5,438

7 Claims. (Cl. 22—92)

The present invention relates to a machine for forming metals, originally in a fluid or plastic form, in a permanent mold whose contour conforms to that of the desired finished article. 5 More particularly my invention is applicable to the pressure casting of relatively high melting point metals and materials.

Some of the more definite objects of the invention are to provide a machine: wherein the metal 10 is forced into the permanent mold or die by the shortest possible route; wherein the entrapment or occlusion of air or gas in the metal or casting is substantially eliminated; wherein the temperature and the transfer of heat to the halves of the 15 die or mold are substantially equal; wherein the means for forcing the metal under pressure into the mold is separate from the mold and thereby may be maintained at a relatively higher temperature without transferring its heat to the latter between casting operations; wherein an auxiliary pressure means is provided for applying an 20 additional casting pressure upon the metal in the mold after the primary pressure means has first introduced the metal thereto, thus insuring an accurate and clean-cut casting conforming to 25 every contour of the mold and further producing a greater refinement of the grain structure of the cast metal.

Additional objects of the invention are: to provide 30 a toggle link mechanism for opening and closing the die plates supporting the mold or die blocks wherein the amount of movement of the respective die plates may be adjustably regulated; to provide a more compact form of hydraulic actuating mechanism for such toggle link mechanism 35 wherein a movable cylinder cooperates with a fixed piston; to provide means whereby the distance of one of the die plates with respect to the moving mechanism may be adjustably regulated 40 in order to accommodate the difference in sizes of interchanged die blocks; and to provide means cooperating with the movement of such cylinder whereby there is obtained a large automatic ejection of the casting. Additional objects 45 and advantages of the invention shall become apparent as the following description proceeds.

To the accomplishment of the foregoing and related ends, said invention, then, consists of the 50 means hereinafter fully described and particularly pointed out in the claims.

The annexed drawings and the following description set forth in detail certain mechanism embodying the invention, such disclosed means 55 constituting, however, but one of various me-

chanical forms in which the principle of the invention may be used.

In said annexed drawings:

Fig. 1 is an elevational sectioned view of a pressure casting machine illustrating an embodiment of the principle of the invention wherein the mold or die block is in closed position; Fig. 2 is a view similar to Fig. 1 but wherein the mold or die blocks are in open position; and Fig. 3 is a fragmentary elevational sectioned view of an alternative form of construction of the link mechanism; Fig. 4 is a view similar to Fig. 3 but showing the link mechanism in collapsed position; Fig. 5 is a sectional view taken upon a plane normal to that of Fig. 1 and substantially along line 5—5 thereof; and Fig. 6 is a fragmentary view illustrating an alternative form of construction wherein an auxiliary cylinder and piston are employed to supplement the action of the main cylinder and piston.

Now referring more particularly to the drawings, and Figs. 1 and 2 thereof, there is shown a base 1 having the upstanding supports 2 and 3 in the upper ends of which the horizontal supporting bar 4 is slidably carried. It will be understood that there are two of these supporting bars 4, but only one of which is illustrated in Figs. 1 and 2. Die plates 5 and 6 are mounted upon the supporting bars 4 and are also connected to an additional pair of upper supporting bars or tie rods 7. The die plate 5 is slidable upon the supporting bars 4 and 7, and the die plate 6 is secured to such bars by means of suitable fasteners such as the nuts 8 and 9. The die plates 5 and 6 each carry the respective halves 10 and 11 of the die block or mold. The parting line 12 of the mold, which is also the meeting face of the die block halves 10 and 11 is enlarged as at 13 where it registers with the open end of the pressure casting cylinder 14.

A piston 15 is positioned within the pressure casting cylinder 14 and is connected by means of the rod 16 to the piston 17 which in turn is mounted within the hydraulic cylinder 18. Tie bars 19 connect the cylinder 18 to the machine base 1. Hydraulic pressure inlets and outlets, only one of which is shown as at 20, lead to a pressure source whereby fluid such as oil under high pressure may be admitted to either end of the cylinder 18 and thereby operate the piston 17 and its connected pressure casting piston 15.

The interior 21 of the piston 15 is hollow and occupied by a baffle strip 22 which effects the circulation of a cooling medium such as water cir-

culated through the flexible connections 23 and 24 on the side of the piston 15.

The left hand ends, or the ends of the rods 4 and 7 which are opposite to the die plate 5 are secured to the plate 25 by means of the nuts 26. A piston rod 27 is also connected to the tie plate 25 by means of the nuts 28 and 29. The piston rod 27 carries the piston 30 on its outer end. The piston 30 is of course in a fixed position and is enclosed by the movable cylinder 31. Laterally projecting lugs 32 on the side of the cylinder 31 connect the latter by means of the links 33 to the movable pivots of a dual toggle link mechanism. This latter mechanism consists of the links 34 pivotally connected to the end of the projections 35 on the tie plate 25, and also pivotally connected to the links 36, which latter links connect as at 37 to the movable plate 38. The plate 38, it will be understood, is carried by the tie bars 4 and 7 and is free to slide thereon.

A screw jack mechanism connects the die plate 5 to the movable plate 38. This die plate mechanism consists of a hollow cylindrical member 39 whose outer wall carries a screw thread 40 threadably engaging with the movable plate 38. The right hand end of the cylindrical member 39 is rotatably secured to the die plate 5 by means of the shoulder 41 which is held in place by an abutment ring 42. Suitable fastening studs 43 secure the ring 42 to the body of the die plate 5. A shaft 44 (Fig. 5) is journaled in the die plate 5 and carries a worm 45 which in turn meshes with the worm gear track 46 on the exterior of the end of the cylindrical member 39. A crank arm 47 is mounted on the outer end of the shaft 44 and serves as means for manually rotating the shaft 44 and the worm 45. A bracket 48 is secured to the die plate 5 and carries a split sleeve 49 surrounding the shaft 44, and which by means of a suitable clamp screw (not shown) and threaded through the sleeve 49 as at 50, serves the purpose of clamping the shaft 44 against rotation.

The right hand end of the cylinder 31 is in the form of a piston 51 which travels in the interior of the cylinder member 39. The other end of the cylinder 31 is of course carried by the piston rod 27.

Fluid pressure conduits 52 and 53 lead from the outer left hand end of the piston rod 27 and communicate with both the rod end and the head end of the piston 30 as at 54 and 55 respectively. A check valve 56 in the end of the cylinder 31 serves as means for retaining fluid in the passages 57 and 58, which when ejected by the entry of the end 59 into the reduced diameter end portion of the cylinder 31, effects a cushioning action between the movement of the cylinder and piston at the end of the stroke illustrated in the position of Fig. 2.

A bar 61 is secured to the vertical support 2 by means of fastening nuts 62 and 63. The bar 61 extends through openings in downwardly depending projections 64 and 65 on the tie plate 25 and the movable plate 38 respectively. The majority of the right hand portion of the bar 61 is threaded and double lock nuts 66 and 67 are threaded thereon and serve as limit stops for the movement of the movable plate 38. A nut 68 threadably engages the left hand end of the rod 61 and limits the left hand movement of the tie plate 25.

The operation of the apparatus above described is as follows:

At the beginning of the cycle of operations the respective parts are in the position as shown in

Fig. 2. A quantity of molten metal which is to be cast is ladled into the open end of the cylinder 14. Next hydraulic pressure is introduced into the passage 53 in the piston rod 27 and the cylinder 31 is forced to its right hand position as indicated in Fig. 1, coincidentally, the toggle link mechanism operates to draw the die plates 5 and 6 toward each other, whereby the die blocks or two halves 10 and 11 of the mold are moved into closed position above the end of the pressure cylinder 14. Next hydraulic pressure is admitted through the passage 20 into the head end of the cylinder 18 and the piston 15 thereby forced upwardly in the casting cylinder 14 to force the metal into the mold. In the next step of operations, hydraulic pressure is introduced into the passage 52 in the piston rod 27; the cylinder 31 is moved to its left hand position as shown in Fig. 2, the toggle link mechanism correspondingly operated, the die plates 5 and 6 moved apart and the die blocks or mold halves 10 and 11 are opened to free the resultant casting C.

It is to be understood, of course, that various types and sizes of die blocks or mold halves 10 and 11 are to be interchanged on the faces of the die plates 5 and 6. Due to the different sizes in such die blocks or to the particular conformation of the casting, it is desirable that the die plates be moved to different positions with respect to the end of the cylinder 14 when in open position. Such a regulation of the variation in the open positions of the die plates 5 and 6 is attained by adjustment of the set of lock nuts 66 and 67 on the rod 61. Thus, if it is desired to move the die plate 6 to a position further toward the right with respect to the position shown in Fig. 2, the lock nuts 66 are moved to a position further to the right on the bar 61 with the result that the movable plate 38 will be stopped sooner in its left hand movement by reason of the projection 65 abutting against the lock nuts 66. The limitation of this left hand movement of the movable plate 38 will be transmitted through the links 33, 34, and 36 to the tie plate 25, through the bars 4 and 7 to move the die plate 6 to a further right hand position.

Where it is desired to provide a large automatic casting ejecting action, the form of construction illustrated in Figs. 3 and 4 may be employed. Reference numerals referring to equivalent elements of the construction already described in connection with Figs. 1 and 2 are given a prime marking in Figs. 3 and 4. In the latter illustrated construction, gear racks 70 are provided on the outer wall of the movable cylinder 31'. These gear racks 70 are engaged by the segmental gears 71 rotatably mounted on the tie plate 25' at the point 72, 72. The segmental gears 71 carry the rigid link arms 73 which in turn connect to the link 74 in turn pivotally connected to the movable plate 38'.

Ejector pins 75 and 76 extend through the die plate 5' and into the interior of the hollow screw jack 39'. An interiorly threaded member 77 projects from the right hand end of the movable cylinder 31 and threadably engages with the rod 78 carrying the abutment plate 79. The plate 79 is slidable in the interior of the hollow screw jack 39' but is locked against rotation with respect thereto by means of the key 80 engaging in the keyway 81.

Thus, when the die plate 5' is moved to open position as shown in Fig. 4, the abutment plate 79 moves into the interior of the hollow cylinder 39', and contacts with the end of the ejector pins 75.

15 and 16 to force the latter in a right hand direction and thereby to eject the casting from the mold. Rotation of the screw jack 39' in order to regulate the position of the die plate 5' with respect to the movable plate 38' will be transmitted to the rod 18 to thereby rotate the latter's threaded engagement with respect to the member 11 and to automatically regulate the position of the abutment plate 19 with respect to the end of the movable cylinder 31'.

In the alternative form of construction shown in Fig. 6 a small high pressure auxiliary casting cylinder 85 is provided in the wall of the die plate 6. A piston 86 operates in this cylinder 85, the open end of which communicates by means of the passage 87 to a point adjacent the open end of the main pressure cylinder 14. The piston 86 is connected to the hydraulic pressure piston 88 in the cylinder 88.

In the operation of the last described form of construction, the main pressure casting piston 15 will be operated to first force the metal into the mold, and remain or lock at the end of its pressure casting stroke, and then the small auxiliary piston 86 will be actuated in order to apply additional pressure on the metal in the mold and thereby to insure contact of the metal with all points of the mold and also to produce a refinement of grain structure in the casting due to the exertion of such additional pressure.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a pressure casting machine, the combination of a pair of die plates, supporting bars extending from the first of said plates to a position beyond the other, toggle link mechanism connected to one end of said bars and at the other end to a screw jack, the latter carrying said second die plate.

2. In a pressure casting machine, the combination of a movable die plate, means for movably supporting said die plate, a screw jack carried by said supporting means for regulating the distance of said die plate with respect to said supporting means, worm and gear means connected to said screw jack, and operating means for said worm and gear operable from the exterior of said machine.

3. In a pressure casting machine, the combination of movable die plates, a toggle link mechanism adapted to move said plates, said link mechanism comprising an end fixed to a tie plate and laterally movable elements, a cylinder connected to said laterally movable elements, a piston in said cylinder having its rod end connected to said tie plate whereby relative movement between said cylinder and piston operates to collapse and extend said link mechanism, one end of said cylinder being slidably supported on the rod of said piston, and a guide member carried by the other end of said link mechanism for supporting the other end of said cylinder.

4. In a pressure casting machine, the combination of a pair of die plates, supporting bars extending from the first of said plates to a position beyond the other, a toggle link mechanism connected to one end of said bars and at the other end to a screw jack, the latter carrying said second die plate, said link mechanism including laterally movable elements, a cylinder connected to the laterally movable elements of said link mechanism, a piston in said cylinder and having its rod end connected to said supporting bars, said cylinder being slidably supported at one end on the rod of said piston and slidably supported at the other end in the interior of said screw jack.

5. In a pressure casting machine, the combination of a pair of die plates, supporting bars extending from the first of said plates to a position beyond the other, a toggle link mechanism connected to one end of said bars and at the other end to a screw jack, the latter carrying said second die plate, said link mechanism including laterally movable elements, a cylinder connected to the laterally movable elements of said link mechanism, a piston in said cylinder having its rod end connected to said supporting bars, said cylinder being slidably supported at one end in the interior of said screw jack, the interior of said screw jack being hollow, casting ejector pins extending into the interior of said screw jack, and a member threadably attached to the end of said cylinder and adapted to contact with said ejector pins, said member being slidably and non-rotatably attached to the interior of said screw jack whereby rotation of the latter operates to regulate the position of said member with respect to the end of said cylinder.

6. In a pressure casting machine, the combination of a pair of die plates, supporting bars extending from the first of said plates to a position beyond the second, toggle link mechanism connected at one end to said bars and at the other end to said second die plate, and means for limiting the movement of said second die plate and adapted to cause additional movement of said toggle link mechanism to be transmitted through said supporting bars to said first die plate.

7. In a pressure casting machine, the combination of a pair of die plates, supporting bars extending from the first of said plates to a position beyond the second, toggle link mechanism connected at one end to said bars and at the other end to said second die plate, and adjustable limit stops attached to the base of said machine for limiting the movement of said second die plate and adapted to cause additional movement of said toggle link mechanism to be transmitted through said supporting bars to said first die plate.

WILLIAM M. LESTER.
